SOUVENIR OR MESSAGE BOX

Andrew Formoso, Washington, D. C.

Application November 8, 1935, Serial No. 48,911

6 Claims. (Cl. 206—1)

This invention relates to improvements in souvenir or message boxes and a primary object is to provide a drawer-containing box having a novel opening arrangement.

Another object of the invention is to provide a box so constructed that a person inexperienced in receiving the same will readily visualize what must be done in order to gain access to its contents.

A further object of the invention is to provide a message box suitable for postal purposes, and having an exterior appearance and shape somewhat similar to a conventional postal envelope.

A still further object is to provide a message box having both locking and sealing means whereby the contents of a message during transmission may be safeguarded.

Another object of the invention is to provide a decorative message box which may be economically manufactured, and which may be preserved indefinitely by the recipient as a souvenir of the occasion.

Other objects and advantages of the invention will be apparent during the course of the following detailed description taken in connection with the accompanying drawing forming a part of this specification and in which drawing:—

Figure 1 is a top plan view of the improved message box.

Figure 2 is a bottom plan view thereof.

Figure 3 is a view in side elevation of the message box and showing a slide positioned in the side thereof.

Figure 4 is a horizontal sectional view of the improved message box.

Figure 5 is a cross-sectional view along the line 5—5 of Figure 4.

Figure 6 is a perspective view illustrating a preferred step being taken during the opening of the message box by a recipient thereof.

In the drawing illustrating a preferred embodiment of the invention, and wherein the same reference characters designate the same or corresponding parts throughout the several views, the letter A generally designates the improved souvenir or message box, which comprises a casing B having an open side adapted to be closed by means of a slide C; a drawer D of a size to fit within said casing and removable thru said open side; and a sheet E of paper secured within the drawer, which sheet may be provided with a suitable message printed, written or otherwise placed thereon.

The casing B may include a top wall 10, a bot-

tom wall 11, a pair of end walls 12, and a back wall 13, forming a chamber 14, access to which may be had thru an open wall or side 15. The inner surfaces of the top and bottom walls along their marginal edges 16 and 17 adjacent said open side 15 may be grooved or channelled to provide a slideway 18. The top wall 10 may be provided with a preferably arcuate notch 19 substantially bisecting the marginal edge 16 and extending into the top wall 10 a substantial distance beyond 10 a slideway 18. The exterior surfaces of the casing may be decorated with pictures of natural scenes, such as of water, mountains, trees, etc.; or with portraits or drawings of famous persons, buildings, memorials, or places. Space may be reserved on the exterior of the top wall 10 for the placing of a postage stamp and a post office address. Lines 19 may be provided on the bottom wall 11 whereby the outlines of an envelope flap will be simulated and within these outlines, a space may be reserved for a return address.

As to slide C, it may comprise a thin strip of any suitable material, such as wood, of a length equivalent to that of the open side 15 and of a width to snugly fit in the slideway 18. A flat inner side 20 and a beveled or arcuate outer side 21 form sharp longitudinal side edges along the slide, for frictionally engaging the grooved or channelled slideway. A niche 22 may be provided in the outer side 21 of the slide preferably near an end thereof.

Referring now to the drawer D, it may be of a size substantially corresponding to the size of chamber 14 within which it is normally positioned. The drawer may include a bottom 23, and sides 24, providing a shallow interior space 25. A cavity 26 may be formed in the top inner margin 27 of one of the sides 24 of said drawer.

It is preferred that the sheet E, which may be of paper, cloth, or other suitable material, be secured in the drawer with at least a portion of same in sealed relation. The sheet may be approximately three times as long as the drawer space 25 is wide, and it may be substantially as wide at one end 28 as the drawer space 25 is long. This end 28 may be provided with adhesive coatings 29 and 30 on the lower and upper margins thereof as shown in Figure 5. The sheet may be of reduced width at its other end 31, the reduction preferably being made in approximately one-third the length of the sheet, and whereby approximately two-thirds the length of the sheet will be of substantially uniform width.

In placing the sheet in the drawer-space, the

end 28 may be positioned adjacent the rear wall of the drawer and adhered to the bottom thereof by means of adhesive coating 29. By folding the sheet on itself once at the front of the drawer 5 as at 32 and again at the rear of the drawer as at 33, the sheet may be positioned within the drawer space with the tapered or reduced end 31 resting in the cavity 26 of the front wall of the drawer. The drawer may then be inserted in 10 the casing with the wall including the cavity 26 adjacent the open side 15 of the casing whereupon the cavity 26 should align with the notch 19 in the top wall of the casing. When the slide is placed in the slideway, the drawer will be securely held in the casing. It will be noted from an inspection of Figures 1 and 5 of the drawing that the arcuate notch 19 extends inwardly a 15 distance sufficient to disclose the upper edge of the slide, and a portion of the drawer wall including the cavity 26 containing the reduced end 31 of the sheet E. At least one end of the slide should be of a size capable of insertion thru the notch 19 and into or in back of the cavity 26 when the drawer is normally positioned in the 20 casing.

The casing and the drawer may each be formed of a single block of wood or other suitable material, by gouging, drilling, boring or otherwise producing the required chambers and recesses 30 therein if this is found to be more desirable than forming the same of several elements joined together as by gluing. To use the improved souvenir and message box a person desiring to send a message will entirely withdraw the slide from the open side of the casing, as by inserting the thumb nail in niche 22 of the slide. With the slide in the right hand, and the box in the left hand, an end of the slide may be inserted thru notch 19 and positioned in the cavity 26 of the 35 drawer, as illustrated in Figure 6. The drawer may then be quite easily withdrawn from the casing by pulling or otherwise manipulating the slide. The tab-like end 31 of sheet E may be pulled upwardly and forwardly whereupon the sheet will unfold to a substantially flat condition. After writing or printing the desired message or other indicia thereon, the sheet may be refolded and, if desired, may be sealed by means of the adhesive coating 30, thereby preventing the 40 unfolding of the sheet for the purpose of reading the message without first breaking the seal. The drawer may then be placed in the casing and securely retained therein by positioning the slide in the open side thereof. The message box may 45 be suitably addressed and the proper postage applied thereon and is then ready to mail.

Upon reaching its destination, the message box will quite naturally be examined by its recipient, who will observe portions of the slide C, drawer 60 D and sheet E thru the notch 19. The recipient may also observe the niche 22 at one end of the slide. With these clues, a person inexperienced in opening a message box of this kind will promptly realize that the first step to be taken in opening 65 the message box is to withdraw the slide and that the thumb nail may be caught in the niche to facilitate its withdrawal. Upon doing this, the recipient will find that the message box is being held in his left hand while the slide is carried in his right hand. It will then become obvious to the recipient that the end of the slide may be utilized as a sort of prying tool for extricating the drawer. Finally, after the drawer has been pulled out, the tab-like end 31 of the sheet E will 70 catch the eye and the recipient of the message

box will quickly note that it offers a convenient means for unfolding the sheet and for tearing or breaking the seal.

Thus it will be seen that a souvenir or message box is provided which is especially suitable for mailing to relatives, friends and acquaintances, and which is somewhat similar in exterior appearance to a conventional postal envelope. 5

Various changes may be made to the form of the invention herein shown and described, with- 10 out departing from the spirit of the invention or the scope of the following claims.

I claim:

1. A box of the class described comprising a casing having an open side, a drawer in said casing 15 removable thru said open side, said casing being provided with a notch in an edge along said open side, said notch communicating with the interior of said drawer, a slideway along said open side, and a slide removably mounted in said slideway 20 and retaining said drawer in said casing.

2. A box of the class described comprising a casing having an open side, a drawer in said casing removable thru said open side, a sheet of writing material adhesively secured to the inside 25 of said drawer, said casing being provided with a notch in an edge along said open side, said notch communicating with the interior of said drawer, a slideway along said open side, and a slide removably mounted in said slideway and retaining 30 said drawer in said casing.

3. A message container comprising a casing having an open side, a drawer in said casing removable thru said open side, a sheet of writing 35 paper adhesively secured to the inside of said drawer, a slideway along the open side of said casing, and a slide removably mounted in said slideway and retaining said drawer in said casing.

4. A box of the class described comprising a casing having an open side, a drawer in said casing removable thru said open side, said casing being provided with a notch in an edge along said open 40 side, said notch communicating with the interior of said drawer, a slideway along said open side, and a slide removably mounted in said slideway and retaining said drawer in said casing, 45 said slide having an end of a size capable of insertion in said notch for engagement with said drawer whereby removal of the drawer from the casing is facilitated.

5. A message box comprising a thin, flat envelope-shaped casing having an open side and a notch in an edge along said open side, a drawer removably positioned in said casing and having a cavity in a portion thereof adjacent said open 55 side, said cavity and said notch being in substantial alignment, and a sheet of writing paper within said drawer and having an edge portion resting in said cavity whereby said edge portion may be observed thru said notch from the exterior of 60 the casing.

6. A message box comprising a thin, flat envelope-shaped casing having an open side and a notch in an edge along said open side, a drawer removably positioned in said casing and having a cavity in a portion thereof adjacent said open 65 side, said cavity and said notch being in substantial alignment, a sheet of writing paper within said drawer and having an edge portion resting in said cavity whereby said edge portion may be observed thru said notch from the exterior of 70 the casing, a slideway along the open side of said casing, and a slide removably positioned in said slideway and retaining said drawer in said casing.

ANDREW FORMOSO.
